UNITED STATES PATENT OFFICE.

ELLERY L. HAMMOND, OF SAYRE, PENNSYLVANIA.

COMBINED TWEEZERS AND FILE.

1,143,761.

Specification of Letters Patent. Patented June 22, 1915.

Application filed March 20, 1914. Serial No. 825,969.

To all whom it may concern:

Be it known that I, ELLERY L. HAMMOND, a citizen of the United States, residing at Sayre, in the county of Bradford and State 5 of Pennsylvania, have invented certain new and useful Improvements in Combined Tweezers and Files, of which the following is a specification, reference being had therein to the accompanying drawing.

10 This invention relates to a combined tweezer and file.

The object of my invention is to provide a neat and compact construction comprising very few parts and adapted to be folded so 15 as to be carried in the pocket.

A further object of my invention is to provide a pivot for the file member eliminating the use of a separate pivot pin.

A still further object of my invention is to 20 provide a handle provided with a recess intermediate its ends to permit the opening of the file.

With these and other objects in view the 25 invention comprises the novel features of construction and combination of parts more fully hereinafter described.

In the drawings: Figure 1 is a plan view of the device with the file member in its closed position. Fig. 2 is a sectional view on 30 the line $\alpha-\alpha$ of Fig. 1. Fig. 3 is a similar view to Fig. 1 with the file member shown in its open position. Figs. 4 and 5 are front elevations showing the file member in its closed and open positions respectively.

35 The numeral 1 designates the handle composed of a single piece of metal folded throughout its length to provide spaced sides 2, the sides 2 being spaced apart and connected with each other by a top connecting portion 3. At one end the sides of the handle 1 are provided with stamped in trunnions 4 and 5, the said trunnions adapted to be seated in an aperture 3' passing through the file member 4' to form a supporting 40 pivot for the said file 4' making it unnecessary to use a separate pin.

Intermediate the ends of the handle is an arc shaped opening 7 extending through the

top connecting portion of the handle and substantially half way through both the 50 sides of the handle, so that when the file 4' is to be used it is only necessary to insert the finger in the arc shaped opening 7 which will press the free end of the file out of the handle so that the same may be grasped by 55 the hand to open the said file. It will be noted that when the file 4' is opened the top connecting portion 3 forms a support for the file. At the opposite end of the file the side handle portions gradually taper, the 60 tapering beginning where the top portion 3 is cut away. These sides also taper from the lower portion of the handle. The top portion 3 is cut away to allow the sides of the handle near its reduced end to be free. 65 The side portions at this point are forced apart as at 5' and have their ends 6 bent inwardly thereby forming tweezers.

From the foregoing description it will be apparent that I have devised an inexpensive 70 article in which the file may be easily opened and also provided a very meritorious form of tweezers construction without altering the stability of the handle. It will also be noted that my form of pivot for the file is very 75 simple and contains a number of advantages as it does away with the necessity of using separate pivot pins.

What I claim is:

In an article of the character described, 80 a body part adapted to be folded upon itself in a substantially U-shaped cross section, with the sides separated at one end and outwardly bowed, so as to construct tweezers, and the sides at the opposite end having inwardly struck-up parts to constitute a bearing, and an extension part normally housed within the body part and adapted to swing 85 on said bearing.

In testimony whereof I affix my signature 90 in presence of two witnesses.

ELLERY L. HAMMOND.
